PROPELLER

Ralph K. Odor, Edmond, Okla., assignor to The Vornado Trust, Oklahoma City, Okla., a fiduciary trust of Oklahoma

Application March 9, 1945; Serial No. 581,740

8 Claims. (Cl. 170—159)

1

This invention relates to propellers, and a principal object is to provide a propeller blade of generally improved characteristics as herein-after more fully set forth.

More specifically, an object of the invention is to provide a propeller exhibiting a materially increased capacity for moving air or other fluid as compared with the propellers of the prior art.

Another object of the invention is to provide a propeller capable of projecting a stream of air over materially greater distances than has been possible with propellers of the prior art.

Contributing to this latter objective, the invention further contemplates provision of a propeller blade having a formation which permits the root portion thereof to participate to a materially greater degree than heretofore considered possible in the primary function of the blade to move air or other fluid.

The invention resides further in certain of the structural details of the blade hereinafter described and illustrated in the attached drawings wherein:

Fig. 1 is an axial view of a propeller blade made in accordance with the invention;

Fig. 2 is a tip end view of the blade shown in Fig. 1;

Fig. 3 is a face view of the blade;

Fig. 4 is a section on the line 4—4, Fig. 3;

Figs. 5, 6, 7, and 8 are transverse sectional views of the blade taken respectively in planes indicated by the reference letters *a*—*a*, *b*—*b*, *c*—*c*, and *d*—*d* in Fig. 1;

Fig. 9 is an axial view of a propeller having blades made in accordance with the invention;

Figs. 10, 11, 12 are diagrammatic views illustrating the physical characteristics of the blade and the manner in which it may be laid out for construction; and

Fig. 13 is a development of the conical surface and diagram of Fig. 12.

With reference first to Figs. 1 to 8 of the drawings, the blade therein illustrated as one embodiment of the invention comprises a cylindrical hub 1 to which the blade 2 is secured through the medium of a fitting 3; said fitting having a flange 4 which is suitably attached to the hub and a projecting portion 5 shaped in conformity to the contour of the root of the blade and to which the blade is secured by means of rivets 6. It will be understood that in the aforesaid figures of the drawing, a single blade has been shown for purpose of illustration, and that a complete propeller would preferably employ two or more such blades uniformly spaced around the axis of the hub in

2

accordance with the conventional practice, as illustrated, for example, in Fig. 9.

With further reference to the drawings, the thrust face 7 of the blade 2 exhibits curvature both radially (with respect to the axis of the hub) and transversely between the leading edge 8 and the trailing edge 9, as best illustrated in the sectional views of Fig. 4 and Figs. 5 to 8 inclusive. It is to be noted that both the radial and transverse curvatures of the face decrease progressively from the root 10 of the blade toward the tip 11. Still further, and with further reference to Figs. 5 to 8 inclusive, the blade angle also decreases from the root toward the tip of the blade. In the present instance, the blade back corresponds in form to the thrust face, the blade being of substantially uniform thickness throughout.

The particular shape and contour of the blade is a function of the curved surface of a right cone, and the thrust face 7 of the blade substantially defines an area of said curved surface. Thus the lobe of the blade, which includes the tip portion 11 and the major area of the blade surface exclusive of the root 10, appears on the curved surface of the cone as an approximate circle, indicated in Fig. 10 by the reference numeral 12, which is centered, preferably, in a point predeterminedly related to the height and radial dimensions of the cone and with reference to the dimensions of the blade, as hereinafter set forth. The longitudinal center line of the blade appears on the surface of the cone as a line 13 which intersects the approximate center 14 of the circle 12 and which extends at an acute angle to a right line 15 on the surface of the cone extending from the apex 16 and also intersecting the approximate center 14. In the present instance, this angle α between the said center line 13 and the right line 15 is approximately 30°. The rotary axis of the blade and of a propeller in which the blade is employed is indicated on the surface of the cone by a line 17 which intersects the line 13 at right angles, and it is to be noted that this axial line 17 is located at a point relatively close to the apex 16 as compared with the tip portion of the blade which may be indicated by the point 18 where the center line 13 intersects the lower side of the circle 12. The root portion of the blade is defined by two lines 19 and 20 which extend from the opposite sides of the circle 12 to the point where the center line 13 intersects the axis line 17, this point of intersection being designated by the reference numeral 21; and it is to be noted that the area of the curved surface of the cone which

is embraced by the lines 19 and 20 and the circle 12 and which represents the outline of the propeller blade is so disposed that the part of the said area which corresponds to the tip portion of the blade is more remote from the apex of the cone than the part of the area which corresponds to the root of the blade and that these parts are offset respectively to opposite sides of a right line represented, for example, by the line 15 which extends on the cone surface from the apex of the latter. It is apparent that with this arrangement the longitudinal center line 13, representing the major radial dimension of the blade, will be curved, and that the elements in the transverse direction between the leading and trailing side edges of the blade will also be curved as previously set forth. By reason of the fact that the root portion of the blade is closer to the apex than the tip portion, the curvatures of the blade both radially and transversely will be more acute in the root portion than in the tip portion.

It will be apparent from the foregoing description that the blade, entirely aside from the general curvature characteristics set forth, will have a special contour constituting a function of the conical surface on which the blade is patterned and that these contour characteristics will vary somewhat in accordance with the angular position of the line representing the axial center line of the blade on the conical surface. Thus, if the line 13 were arranged so that the angle α is less than that shown in the drawings, the pitch of the blade will be correspondingly decreased, it being apparent that when the line 13 is in conformity with the line 15, the blade angle will be 90° throughout and the pitch zero. Similarly, a rearrangement of the line 13 in the opposite direction from the position shown in the drawing will tend gradually to increase the pitch to a maximum where the line 13 lies in a plane normal to the vertical axis of the cone, such plane being indicated in the drawings by the line 22. In any of the various positions which the line 13 might assume between the lines 15 and 22, certain essential characteristics related to the conical surface will be retained. In general, I have found that the disposition of the radial center line 13 as shown in the drawings, in the neighborhood of 30° removed from the line 15, will afford a propeller of desirable overall characteristics, although it is apparent that for special purposes, a blade configuration corresponding to a different position of the line 13 may be found more suitable.

The specific manner of laying out the blade in accordance with the invention is as follows:

A right cone is selected wherein the height as measured on a line normal to the base and intersecting the apex is equal to the diameter of the base. A line is then drawn around the curved surface of the cone parallel to the base at a vertical distance from the apex corresponding to the desired radius of the fan. The diameter of the cone at this line will be equal to the height. In Figs. 10 to 13 inclusive, the reference numeral 22 indicates this circumferential line. The circle 12 is then inscribed on the curved surface of the cone from a center in the line 22 and with a diameter equal approximately to 3/4 of the radial length of the blade which in this instance is, say, 8". The circle 12 will, therefore, having a radius of 3". The right line 15 is then drawn from the apex through the center 14 of the circle 12, and the line 13, corresponding to the longitudinal center line of the blade, is drawn through the

center 14 at an angle to the line 15 determined by the desired pitch of the blade. The geometrical pitch of the blade is in part a function of the blade angle, and the relationship between the value of the angle α and the blade angle is indicated in the present instance by the fact that the said angle α corresponds approximately to the blade angle at the line 13 through the outer portion of the blade, as illustrated in Figs. 1 and 10 to 5. As set forth above, the value of 30° for the angle α has been found to afford a blade of highly desirable characteristics.

The determination of the position of the line 13 also establishes the point on the circle 12 corresponding to the extreme tip of the blade, this point being indicated by the reference numeral 18, as set forth. The next step is to determine the position of the rotary axis of the blade, and this is done by laying off a cord 8" in length from the point 18 along the curved line 13. In Fig. 11 the point where the cord meets the line 13 is indicated by the numeral 21. The said axis of the blade may then be indicated by a line 17 at right angle to the line 13 through this point 21. The line 19 which corresponds to the root section of the leading edge 8 of the blade is then laid off, this being in the nature of a straight line tangential to the circle 12 and intersecting the point 21. The line 20 is established by drawing an arc with a radius equal to the diameter of the circle 12 from a center which causes said arc to intersect the point 21 at one end and to join the circle 12 at the other end in a tangential direction. The lines 12, 19, and 20 represents the contour of the thrust face of the blade.

One of the important characteristics of a blade made in accordance with this invention is its ability to project a substantially solid column of air which, by reason of a vortical effect set up in the column by the blade action, tends to resist disintegration and to maintain its form for a relatively extended period, the result being that a propeller incorporating the blade is capable of projecting air over relatively great distances and at relatively high sustained velocities. This characteristic is of material value in creating a circulation or turbulence of air within extended spaces from a single source, and also in moving air in a sustained column over long distances. It has been found, for example, that propellers made in accordance with this invention placed in series at spaced intervals can be made to sustain the moving column described above for indefinite distances.

As pointed out above, the characteristics of the blade and its physical form may be varied within limits by various arrangements of the longitudinal center line 13 upon the cone surface in the layout process. It is to be noted also that while highly satisfactory results are obtainable by using a cone of specified relative dimensions, cones departing from these relative dimensions will still afford a blade of superior characteristics, and it is to be understood that considerable latitude is permitted in these respects. It is to be noted also that while Fig. 13 constitutes a development of the conical surface and associated diagram shown in Fig. 12, the line 20 in both cases is a true arc drawn from a radius corresponding to the true diameter of the circle 12.

I claim:

1. In a propeller, a blade having a thrust face which substantially defines an area of the curved surface of a right cone, the main body of the

blade including the portions more remote from the propeller axis having an outline appearing as a circle inscribed on said surface from a center in the latter, and the root portion of the blade appearing on said surface as a projection from an arc of the circumference of said circle and having edges merging smoothly into said circumference and converging toward a point on the said conical surface located closer than said center to the apex of the said cone, said blade being disposed with respect to the propeller axis so that a plane normal to said axis will intersect both the said point of convergence and the said center; the line on the surface of the cone which corresponds to the intersection of said plane with the said face of the blade, and the line on the surface of the cone which corresponds to the intersection with said conical surface of a plane containing both the axis of the cone and the said center, diverging from said center at an angle in excess of zero and not exceeding forty-five degrees, whereby the blade will have curvature in directions both radially of the blade and transversely between the leading and trailing edges of the latter.

2. A propeller according to claim 1 wherein the said angle of divergence is approximately 30 degrees.

3. A propeller according to claim 1 wherein the right cone has a base diameter equal to its height.

4. A propeller according to claim 3 wherein the said angle of divergence is approximately 30 degrees.

5. A propeller according to claim 1 wherein the distance of the said point of convergence from the nearest point on the circumference of the circle is equal approximately to one-third of the diameter of the latter, both as measured on the said conical surface.

6. A propeller according to claim 5 wherein the said angle of divergence is approximately 30 degrees.

7. A propeller according to claim 1 wherein the point of convergence of the edges of the said root portion of the blade lies in the axis of the propeller.

8. A propeller according to claim 1 wherein the 15 trailing edge of the said root portion of the blade appears on the conical surface as an arc of a circle having a radius corresponding to the diameter of the circle representing the body portion of the blade.
